US00D601759S

(12) **United States Design Patent**
Ragonetti et al.

(10) **Patent No.:** **US D601,759 S**
(45) **Date of Patent:** **** Oct. 6, 2009**

(54) **BIRDCAGE ATTACHMENT**

(75) Inventors: **Peter Ragonetti**, Brooklyn, NY (US);
Ryan Rutherford, Rutherford, NJ (US);
Jonathan Willinger, Tenafly, NJ (US)

(73) Assignee: **J.W. Pet Company, Inc.**, Teterboro, NJ (US)

(**) Term: **14 Years**

(21) Appl. No.: **29/330,975**

(22) Filed: **Jan. 16, 2009**

(58) **Field of Classification Search** ..... D30/119, D30/160, 199, 133, 121; 119/467, 468, 702, 119/537, 531-533, 705-708, 464, 161, 477, 119/703, 709-711, 469, 57.8, 466; D21/476, D21/408, 407, 468, 596, 475, 398, 474, 467, D21/595; D12/188, 133, 187, 189; 446/227, 446/266, 265, 421, 490, 241, 419, 229, 397, 446/253, 330, 245, 901, 268, 486; 248/908, 248/102, 493, 467, 206.3, 480, 206.4, 279.1, 248/479; 482/132, 46, 129, 24, 87, 86; D24/195; 359/850, 840, 872, 546, 838, 854, 855, 866, 359/871; 132/316; 273/142 R; 74/409; 211/105.2; 264/296, 320, DIG. 66; 5/658; 385/147; 297/135; D6/553, 535, 536, 540, D6/545, 556, 570, 572, 567

(57) CLAIM

The ornamental design for a birdcage attachment, as shown and described.

DESCRIPTION

FIG. 1 is a perspective view of a birdcage attachment;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the design that are shown in broken lines do not form part of the claimed design.
